(57) **CLAIM**

The ornamental design for a rotor blade as shown and described.

DESCRIPTION

1. Rotor Blade
2. Rotor Blade
3. Rotor Blade

1.1: Top view

1.2: Perspective view

1.3: Perspective view

1.4: First enlarged fragmental top view

1.5: Enlarged fragmental perspective view

1.6: Second enlarged fragmental top view

1.7: Bottom view

1.8: Top view

1.9: Bottom view

2.1: Top view

2.2: Perspective view

2.3: Perspective view

2.4: First enlarged fragmental top view

2.5: Enlarged fragmental perspective view

2.6: Second enlarged fragmental top view

2.7: Bottom view

2.8: Top view

2.9: Bottom view

3.1: Top view

3.2: Perspective view

3.3: Perspective view

3.4: First enlarged fragmental top view

3.5: Enlarged fragmental perspective view

3.6: Second enlarged fragmental top view

3.7: Bottom view

3.8: Top view

3.9: Bottom view

Fig. 1.1, Fig. 2.1, Fig. 3.1 are top views of a rotor blade of a wind turbine with attached leading edge protection with a serration part showing respectively the first, second, and third variants of the design; Fig. 1.2, Fig. 2.2, Fig. 3.2 are perspective views thereof; Fig. 1.3, Fig. 2.3, Fig. 3.3 are second perspective views thereof; Fig. 1.4, Fig. 2.4, Fig. 3.4 are first enlarged fragmental top views of a rotor blade tip of a wind turbine thereof; FIG. 1.5, Fig. 2.5, Fig. 3.5 are enlarged fragmental perspective views of a rotor blade tip of a wind turbine thereof; Fig. 1.6, Fig. 2.6, Fig. 3.6 are second enlarged fragmental top views thereof; Fig. 1.7, Fig. 2.7, Fig. 3.7 are bottom views thereof; Fig. 1.8, Fig. 2.8, Fig. 3.8 are top views thereof; Fig. 1.9, Fig. 2.9, Fig. 3.9 are bottom views thereof. The rotor blade of the wind turbine is shown with a symbolic break in broken lines indicating the inde-
